DESIGN FOR A LADY'S WALKING-SKIRT.

SPECIFICATION forming part of Design No. 15,606, dated December 9, 1884.

Application filed August 7, 1884. Term of patent 3½ years.

To all whom it may concern:

Be it known that I, CATHERINE O'HARA, of the city, county, and State of New York, have invented and produced a new and original Design for a Pattern of a Lady's Walking-Skirt, (numbered 9,396;) and I do hereby declare that the engraved prints accompanying this specification convey to any one accustomed to using paper patterns a clear understanding 10 of how a garment made up by the pattern will appear.

The design shows a round walking-skirt, plain across the front and sides. It exhibits a lower back drapery, displaying a broad

double box-plait at each side of the center, 15 and a full, short, puffed upper back drapery drooping over the tops of the lower back drapery and displaying draping plaits at its center and front edges.

What I claim as my invention, and desire to 20 secure by Letters Patent, is—

The design for a lady's walking-skirt, as shown in the engraved prints accompanying this specification.

CATHERINE O'HARA.
